Jersey

Application April 11, 1930, Serial No. 443,299

33 Claims. (Cl. 242—10)

The present invention relates to winding machines.

It is an object of the invention to provide an improved automatic machine, wherein material such as wire is formed into coils; and wherein single- and multiple-layer sheets are supplied thereto in accordance with a desired cycle.

Other objects of the invention will be apparent from the following specification, wherein a preferred and illustrative embodiment of the invention has been selected for purposes of description. In the accompanying drawings:

Fig. 1 is a front elevational view of an automatic machine embodying the present invention; 15 Fig. 2 is an end elevational view of the machine of Fig. 1;

Fig. 3 is a horizontal sectional view of the machine taken on the line 3—3 of Fig. 2;

Fig. 4 is an enlarged detail view of a preferred 20 winding head;

Fig. 5 is a rear elevational view of the structure shown in Fig. 4;

Fig. 6 is an end elevational view of the structure shown in Figs. 4 and 5; 25 Fig. 7 is a detail, transverse sectional view taken on the line 7—7 of Fig. 9;

Fig. 8 is a similar view taken on the line 8—8 of Fig. 9;

Fig. 9 is a horizontal sectional view taken on 30 the line 9—9 of Fig. 4;

Figs. 10 and 11 are front and end elevational views, respectively, of the tail stock for supporting one end of the winding spindle;

Fig. 12 is a detail perspective view of a preferred means for ensuring the return of certain 35 of the control elements of the machine to their starting position prior to the removal of the winding spindle;

Fig. 13 is an enlarged detail elevational view 40 of a pair of wire-guiding rollers on the traverse bar and the associated sheet-transfer means;

Fig. 14 is a vertical sectional view showing the parts just mentioned but taken on the line 14—14 of Fig. 13;

Fig. 15 is a fragmentary, top plan view of the 45 right hand end of the reciprocatory carriage and an associated sheet-engaging finger;

Fig. 16 is an enlarged elevational view of one of the preferred spool-supporting frames and 50 associated wire-tensioning means;

Figs. 17 and 18 are front and rear elevational views, respectively, of the structure of Fig. 16;

Fig. 19 is a horizontal sectional view taken on 55 the line 19—19 of Fig. 16, showing a supply spool mounted on its supporting mandrel;

Fig. 20 is a horizontal sectional view of the structure shown in Fig. 19;

Fig. 21 is a view similar to Fig. 3 but slightly enlarged, with certain parts removed for clear- 60 ness;

Fig. 22 is an enlarged, detail, longitudinal sec- 65 tional view taken on the line 22—22 of Fig. 21;

Figs. 23 and 24 are still further enlarged de- 65 tail vertical sectional views taken on the lines 23—23 and 24—24, respectively, of Fig. 27;

Fig. 25 is a traverse, vertical sectional view through the center of the machine on the line 25—25 of Fig. 22;

Fig. 26 is a fragmentary, front elevational view 70 of a preferred means for adjustably supporting the front of the sheet-transfer means shown on Fig. 25;

Fig. 27 is an enlarged, vertical sectional view 75 taken on the lines 27—27 of Fig. 21;

Fig. 28 is a vertical sectional view taken on the 75 line 28—28 of Fig. 27, showing a preferred mech- anism for actuating the web-severing means;

Figs. 29 and 30 are enlarged, vertical sectional 80 views taken on the lines 29—29 and 30—30, re- spectively, of Fig. 32;

Figs. 31 and 32 are similar views but taken on 80 the lines 31—31 and 32—32, respectively, of Fig. 29;

Fig. 33 is an enlarged, fragmentary, vertical 85 sectional view of the right hand pair of web or paper rolls, with their associated mechanism for drawing a supply of paper therefrom;

Fig. 34 is a rear elevational view of the struc- 90 ture shown in Fig. 33;

Figs. 35, 36 and 37 are enlarged front, end 90 and top views, respectively, of the control means for the paper-feeding means, whereby one sheet or a plurality of superposed sheets may be supplied to the winding spindle;

Fig. 38 is a detail view showing the position of 95 certain of the parts of said control means just prior to the closing of the switch;

Figs. 39 and 40 are front and end elevational 100 views, respectively, of alternative control means for the paper-feeding means;

Fig. 41 is an enlarged view of a spindle pro- 100 vided with a plurality of multi-layer coils, where- in the lead of the last few turns of each coil is increased; and

Fig. 42 is a sectional view through one of the 105 finished coils.

In the following description of the illustrative embodiment of the invention, the illustrative power supply means with its automatic control mechanism will first be described and then, in 110

the sequence indicated, the illustrative mechanism for winding the wire in separated zones on the spindle to form simultaneously a plurality of spaced coils, and the illustrative mechanism 5 whereby single- and multiple-layer sheets of windable material may be supplied at will to the coils under formation.

Referring first to the illustrative power supply means and associated automatic control 10 mechanism, a source of power for the machine may conveniently take the form of an electric motor 1. This motor is suitably mounted on the supporting standards 2 of a main bed-plate or table 3, as shown in Fig. 1. Conveniently, a belt 15 4 extends from the motor 1 to a pulley-wheel supported on a horizontal shaft section 5 rotatably mounted in a winding head 6, as shown in Fig. 9. The winding head 6 is preferably mounted on the bed-plate 3 adjacent to the left 20 front corner thereof.

Preferably, a counting device 7 of known design may be supported on the top portion of the winding head 6, and it is connected by a train of gears 8 to the shaft section 5, as shown generally in Fig. 4. The counting device 7 may conveniently comprise relatively movable portions 9 and 11, respectively, which may be so marked as to indicate the extent of operation of the machine, as, for example, the number of revolutions 25 of the shaft section 5. The portion 11 of the counting device 7 may be provided with a cam abutment 12 which is movable into engagement with an angularly-adjustable lever 13 when the machine has operated for a predetermined time 30 interval. The lever 13 is also suitably mounted on the counting device 7 for pivotal movement, so that when such engagement occurs, the lever 13 is rocked. An inner end of the lever 13 is operatively associated with a movable switch member 35 14, whereby the rocking of the lever 13 may cause the actuation of the switch member 14 from an outer circuit-closing position to an inner circuit-interrupting position. The switch member 14 may be tensioned by means of a spring 40 (not shown) so as to tend to occupy normally its outer circuit-closing position. The circuit controlled by the switch member 14 is preferably the energizing circuit of the driving motor 1. Thus, when the machine has operated for a predetermined 45 time interval and coils of desired dimensions have been formed as will presently appear, the cam abutment 12 engages the lever 13, causing an inward movement of the movable switch member 14 into its circuit-interrupting position and the consequent de-energization of the motor 1 and the stopping of the machine as a whole.

Conveniently, the switch member 14 may be controlled from a foot pedal 15 suitably mounted at the front of the machine adjacent to the driving motor 1, as shown in Fig. 2. The foot pedal 15 is provided with an arm 16 which is connected to an arm 17 rigidly secured on a pivoted arm 18. The arm 18 may constitute the movable member of a motion-retarding device 19, such, for example, as a door check, for reasons as will presently appear. The arm 18 is connected by a link 21 to a crank arm 22, rigidly secured to a rock shaft 23 suitably supported adjacent to the motor 1. The rock shaft 23 is provided with an elongated 55 crank arm 24 having an aperture through which extends a vertical rod 25. The rod 25 is normally held by a spring 26 in the position shown in Fig. 2, wherein an abutment 27 adjustably mounted thereon is disposed just below and in alignment 60 with the crank arm 24.

The vertical rod 25 extends up through an opening in the table 3 and it is secured to one arm of a bell-crank lever 28, the opposite arm of which engages the outer exposed end of the switch member 14 so as to hold the same in its inner circuit-opening position. The bell-crank lever 28 may be tensioned by means of a spring (not shown) so as to tend to move from its dot-and-dash line position shown in Fig. 4 into its solid-line position. The linkage just-described is so designed that the foot pedal 15 may be first moved through a predetermined angle without causing the actuation of the vertical rod 25. A further movement, however, causes the crank arm 24 to engage the abutment 27 and thereby rock the bell-crank lever 28, so that the free arm thereof is moved out of holding engagement with the switch member 14 into the dotted-line position shown in Fig. 4. The switch member 14 then moves into the outer circuit-closing position under the force of its spring (not shown), but the machine remains at rest until the foot pedal 15 has been released, for reasons as will presently appear.

In accordance with the present invention, the driving motor 1 is such that the speed thereof may be gradually increased from starting to normal running speed. As shown in Fig. 2, the motor 1 is provided with movable brush mechanism 29 for controlling the motor speed. Preferably, a spring 30 is provided for returning the brush mechanism 29 from an advanced or neutral position, wherein the motor 1 remains at rest although supplied with energizing currents, to the normal running position shown in Fig. 2 wherein the motor 1 operates at its maximum speed. The brush mechanism 29 is connected by a crank arm 31 to the shaft 23 which carries the crank arm 22. Should the extent of movement of the arm 18 of the door check 19 be greater than that of the brush-shifting mechanism 29, conveniently, a slotted connection 32 may be provided between the link 21 and the crank arm 22, so that the arm 18 may continue to move after the brush-shifting mechanism 29 has been actuated through its maximum movement.

The operation of the apparatus so far described is as follows: the foot pedal 15 is first depressed to cause the actuation of the crank arm 24, as well as the shifting of the brush mechanism 29 from its normal running position to its starting or neutral position. When the brush mechanism 29 moves into its neutral position, the crank arm 24 engages the abutment 27 to cause the actuation of the bell-crank lever 28 from the solid-line position to the dotted-line position shown in Fig. 4, thereby releasing the switch member 14. The switch member 14 then moves into its circuit-closing position and currents are supplied to the motor 1, but, inasmuch as the brush mechanism 29 is in its neutral position, the machine remains at rest.

The release of pressure from the foot pedal 15, however, results in the movement of the brush mechanism 29 from its starting position to its normal running position, shown in Fig. 2, under the force of the spring 30. The movement of the brush mechanism 29 between the two positions is controlled by the door check 19, so that the speed of the motor 1 is gradually accelerated, thereby materially decreasing the initial starting load on the wire and preventing the breakage thereof. The machine now continues to operate until the cam abutment 12 actuates the pivoted lever 13, causing the switch member 14 to be

80

140

145

150

5 moved into its circuit-opening position, whereupon the motor 1 is deenergized and the machine comes to rest. The inward movement of the switch member 14 permits the bell-crank lever 28 to return to its solid-line position, shown in Fig. 4, at which time the machine is again ready for starting. It will be noted that the operation of the motor may be manually controlled independently of the foot pedal 15 merely by operating the 10 switch member 14.

Coming now to the mechanism whereby a plurality of layers of wire may be wound in separated zones to form a plurality of spaced coils, a winding spindle 34 is conveniently supported 15 at its right end on a rotatable center 35 mounted for longitudinal movement in a tail stock 36, as shown particularly in Fig. 10. The center 35 may be actuated from supporting to non-supporting positions, in order that the spindle 34 may be moved, by means of a pinion 37 and a co-operating 20 rack 38 formed on the center 35. A spring 39, which is secured to an operating arm 41 for the pinion 37, serves to retain the center 35 in either 25 of its operative positions. The center 35 may be locked in the supporting position by means which may conveniently take the form shown in Figs. 10 and 11, wherein a tensioned arm 42 is so positioned that a free end thereof engages an adjacent end of the center 35, so that movement 30 of the center causes a movement of the arm 42. The arm 42 may be releasably locked in the position shown by means of a spring-tensioned lever 43, which is provided with a pin 44 positioned to engage normally a notch 45 formed in a lower 35 corner of an arm 46 mounted on a rock shaft carrying the arm 42. The construction is such that, when the lever 43 is moved downwardly against the force of its spring, the pin 44 is actuated out of engagement with the recess 45, permitting the 40 actuation of the arm 42 by the center 35, and hence the removal of the winding spindle 34 from the machine. The lever 43 may be held in this position by means of a tensioned lever 43a. This lever is so disposed with respect to an arm 44a 45 of the lever 42 as to be actuated into an ineffective position upon a movement of said lever 42.

As shown in Figs. 10, 11 and 12, the lever 43 may be actuated by one arm 47 of a bell-crank lever 48, an opposite arm of which is connected by a 50 rod 49 to a crank arm 51 rigidly secured to a rock shaft 52 extending across the full width of the machine and supported in suitable bearings 53 mounted on the table 3 at the ends thereof. The rock shaft 52 is connected to certain control elements of the machine, hereinafter referred to, 55 permitting the resetting of their associated machine parts simultaneously with the release of the center-locking means and the removal of the spindle 34, as will hereinafter appear in greater detail.

The left hand end of the winding spindle 34 is detachably secured, as shown in Fig. 9, to a chuck 54 mounted on the right hand end of the shaft section 5 carried by the winding head 6. Hence, rotation of the shaft section 5 is imparted 60 to the winding spindle 34. A traverse bar 55, which extends horizontally across the front of the machine, is mounted for reciprocation in bearings 56. These bearings are preferably mounted on the front edge portion of an angularly-adjustable frame 57 constituting one part of a sheet-transfer means hereinafter described in detail. The left hand end of the traverse bar 55 may be connected to a horizontal reciprocating 65 bar 58 by means of a clutch 59, which is adapted

70 to maintain a driving connection between the two bars regardless of the angular adjustment of the frame 57. The clutch 59 shown herein for purposes of illustration, comprises a pair of spaced plates 61, which are rigidly secured to the traverse bar 55, and a plate 62 which is rigidly secured to the actuating bar 58 and adapted to fit between the spaced plates 61. The actuating bar 58 may be suitably mounted in bearings on the rear side of the winding head 6, as shown in 75 Figs. 5, 6 and 9.

The horizontal actuating bar 58 may be pivotally connected at 63 to a lever 64, which is fulcrumed at 65 on a member 66 adjustably mounted on a vertical rod 67, whereby the extent of movement of the bar 58 by the lever 64 may be adjusted. The lower end of the lever 64 is pivoted at 68 to a carriage 69 mounted in suitable spaced bearings for horizontal reciprocation. The carriage 69 may be provided with a pair of spaced rolls 71 and 72 which respectively engage opposite points on a traverse cam 73 of heart shape. One of the rolls, say 72, may be spring-pressed as shown particularly in Fig. 5, being mounted on a lever 74 pivoted at 75 on the carriage 69. The lower end of the lever 74 is pivotally secured to a rod 76 which passes through an opening in the frame 69. A spring 77 may be positioned between the frame and an adjustable shoulder 78 on the rod 76, and it is of sufficient strength to maintain the roll 72 in engagement with the cam 73 during the normal operation of the machine. Back lash in the mechanism just-described may be overcome by means of a spring 79 which extends from a free end of the horizontal actuating bar 58 to the winding head 6. The cam 73 is so designed that, for one complete revolution, the traverse bar 55 is actuated through a full stroke to the right and to the left.

The cam 73 may be mounted on a cross shaft 81, one end of which extends through the winding head 6 and is suitably journaled therein. The front end of the cross shaft 81 is conveniently connected by a gear train 82 to a driving pinion 83 actuated by the shaft section 5 through gear-wheel mechanism (not shown). The gear train 82 preferably includes pairs of intermediate gear-wheels 84 and 85, which are removably mounted on an adjustable arm 86, so that the gear ratio of the train 82 may be varied in accordance with changes in the size of the wire, the desired lead and the like.

It is frequently desirable to increase automatically the lead of the last few turns of wire in a layer, as shown in Fig. 41, without stopping the machine. One means for accomplishing this desired result is shown in Figs. 4, 6, 7 and 9, wherein it will be observed that an additional gear train 87 is provided which is positioned adjacent to the winding heads 6 directly in front of the gear train 82. Conveniently, the gear train 87 extends from the front end of the cross shaft 81 to the driving pinion 83, and it may include a gear-wheel 88 which meshes with the driving pinion 83 and a gear-wheel 88a which is mounted on a shaft 89. A hand wheel 91 and one element 92 of a clutch are mounted on an outer end of the shaft 89 and splined thereto. Another element 93 of the clutch is loosely mounted on the shaft 89. A spring (not shown) normally causes the separation of the co-acting clutch elements 92 and 93. The clutch element 93 is rigidly secured to a gear-wheel 94 which is also loosely mounted on the shaft 89. The gear-wheel 94 may be connected through a plurality of change gear- 145

80

85

150

wheels 95 to a gear-wheel 96 rigidly secured to the front end of the shaft 81. Hence, when the clutch element 92 is actuated into engagement with the clutch element 93 by an inward pressure on the hand wheel 91, the gear train 87 is rendered effective to drive the cross shaft 81 at a speed which is greater than that due to the gear train 82, whereby the lead of the wire being wound on the spindle 34 may be increased. Inasmuch as the shaft 81 is now operated at a speed greater than that effected by the gear train 82, it is necessary to provide a lost-motion connection in the gear train 82. This desired result may be conveniently accomplished as shown in Figs. 4 and 9, wherein it will be noted that a plurality of spring-pressed pawls 97 are mounted on the front surface of a gear-wheel 98 loosely mounted on the shaft 81, the pawls 97 co-acting with a ratchet-wheel 99 rigidly secured to an adjacent portion of the shaft 81. Accordingly, when the shaft 81 is operated by the gear train 87 at a greater speed than that effected by the gear train 82, the pawls 97 merely ride over the ratchet-wheel 99. However, when the inward pressure on the hand wheel 91 is released, the clutch element 92 moves out of engagement with the co-acting clutch element 93, rendering the gear train 87 ineffective. The gear train 82 now operates automatically to cause the rotation of the cross shaft 81. It will be observed, therefore, that the change in the lead of the wire being wound on the spindle 34 occurs automatically while the machine is in operation and is controlled merely by the clutch element 92.

As shown particularly in Figs. 13 and 14, the traverse bar 55 may be provided with a plurality of brackets 101 positioned at spaced intervals across the width of the angularly-adjustable frame 57. Each bracket is provided with suitable means, whereby it may be clamped on the traverse bar 55 in the desired adjusted position, the same being herein shown as comprising a set screw 102 for releasably clamping a pair of arms 103 provided with complementary recesses adapted to receive the traverse bar 55. Each of the brackets 101 is also provided with an aperture for a guiding rod 104, which extends across the width of the angularly-adjustable frame 57 and is mounted at its ends in the bearings 56, whereby the traverse bar 55 and the brackets 101 may be further guided during reciprocating movement. The brackets 101 are also provided with a pair of guide rolls 105 and 106, which are positioned directly over the winding spindle 34, the wire to be wound on the spindle passing on opposite sides of these rolls, as shown in Fig. 14. The number of guiding brackets 101 mounted on the traverse bar 55 is dependent upon the number of coils to be wound on the spindle 34, there being one guiding bracket for each coil.

Suitable means are herein provided for supplying the wire to the several guiding brackets 101 and the spindle 34, the same being herein shown generally in Figs. 1 and 2, and more particularly in the enlarged detail views of Figs. 16 to 20, inclusive, wherein it will be noted that a plurality of spool-supporting frames 107 are mounted on a horizontal bar 108 for independent axial and angular adjustment. The bar 108 may be supported at the rear edge of the table 3 on a pair of spaced standards 109. Conveniently, there is one of these frames 107 provided for each pair of brackets 101, inasmuch as each frame carries a pair of spools or bobbins 111. As shown in Figs. 16 to 20, inclusive, each of the angularly-adjustable spool frames 107 comprises a main supporting member 112 having an opening 113 through which the horizontal supporting bar 108 extends. A portion of the member 112 immediately surrounding the opening 113 is provided with a pair of clamping arms 114 and a co-operating bolt 115, permitting the rigid securing of the member 112 on the bar 108 in the desired axial and angular position.

As shown in Fig. 20, each of the spools 111 may be clamped on a rotary mandrel 116 between a stationary abutment 117 and an adjustable, removable abutment 118 of usual design. The mandrel 116 is provided with an extended portion 119, an inner end of which carries a brake drum 120. Between the brake drum 120 and the abutment 117 the portion 119 of the mandrel 116 is journaled in spaced anti-friction bearings 121 carried by a tubular member 122 adjustably supported in a bearing 123 constituting an integral extension of the main-supporting member 112. A set screw 124 may be used to secure the tubular member 122 in desired adjusted position. It is noted that the abutment 117 may be provided with an outwardly extending flange portion 125, which serves to hold the adjacent anti-friction bearing 121 in position. The flange portion 125 may terminate in a transversely extending portion 126 which serves to cover the adjacent corner of the tubular member 122. A similar flange 127 extends from the brake drum 120 over the adjacent corner portion of the tubular member 122, as shown in Fig. 20. In this manner, the spools 111 of each of the frames 107 are rotatably mounted one above the other.

It is desirable that means be provided in addition to the variable-speed motor 1, whereby the initial heavy pull on the wire incident to the starting of the machine may be decreased, as well as the tendency for the spools to overrun during the stopping of the machine. The means for accomplishing this result are shown in Fig. 16, wherein it will be noted that there is associated with each of the spools 111 a tension rod 128 which is secured at its inner end to a block 129 pivoted on the main-supporting member 131. The tension rod 128 conveniently carries a longitudinally adjustable collar 132 for one end of a spring 133, an opposite end of which is secured to an arm 134 mounted at 135 on the main-supporting member 112 for angular adjustment. The spring 133 tends to actuate the block 129 into engagement with a resilient abutment 136 mounted on an adjacent portion of the main-supporting member 112. An outer end of the tension bar 128 is provided with a roller 137 about which the wire from the spool 111 is passed. The block 129 is connected by a link 138 to one arm of a lever 139, the opposite arm of which carries a spring strip 141. The free end of the spring strip 141 has mounted thereon an arcuate brake member 142 which is provided on its inner surface with a brake lining 143 adapted to engage the adjacent surface of the brake drum 120.

The parts just described are so arranged that when the load on the wire increases, as occurs during the starting of the machine, this condition is at least partly compensated for by the downward movement of the tension rod 128 from the solid-line position shown in Fig. 16, to some lower position, such, for example, as the dotted-line position. The downward movement of the tension rod 128 through the linkage 138 and 139 serves to actuate the brake-member 142 away from the brake drum 120, so that the spool 111 is free to rotate. When the load on the wire passes

ing from the spool 111 is decreased, as occurs when the machine is coming to rest, the tension rod 128 moves from its dotted-line position to its solid-line position under the force of the spring 5 133. As a result, the brake member 142 engages the brake drum 120, causing the spool 111 to come to rest rapidly without undesirable over travel.

Proceeding with the description of the mechanism, the means, whereby measured sheets of 10 single- and multiple-layer windable materials of progressively increasing length may be supplied at will to the coils under formation on the spindle 34, is shown in Figs. 21 to 38, inclusive. This means comprises in general a pair of separate 15 paper-supply means, which are suitably positioned in side-by-side relation at the rear of the machine and below the table 3; a pair of separate paper-feeding means for the pair of paper-supply means, respectively, which are conveniently positioned 20 at the rear of the machine but above the table 3; a pair of separate paper-serving means for the webs of paper supplied by the pair of paper-feeding means, which are positioned just in front of and in alignment with the pair of paper-feeding means; and common transfer means, 25 which are positioned at the front of the machine, for moving the severed sheets from the pair of severing means to the common winding spindle 34.

Referring first to the pair of separate paper-supply means, as shown particularly in Figs. 33 and 34, a plurality of roll-supporting frames 144 are suspended from the rear edge of the table 3, and are provided with suitable means for rotatably supporting pairs of paper rolls 145, 146 and 35 147, 148 which are respectively positioned in alignment with the pair of separate paper-feeding means. Thus, a pair of paper-supply rolls is provided for each of the separate paper-feeding means, for reasons as will presently appear. The 40 thickness of the webs of paper in the pair of rolls 145 and 146 may be the same or different, depending upon the electrical characteristics of the coils under formation, and the same is true for the pair of rolls 147 and 148. Conveniently, each of the 45 paper rolls is provided with a brake drum portion 149 for frictional engagement with a brake shoe 151 suitably supported on a spring strip 152 carried by the roll supporting frame 144, whereby over travel of the paper rolls may be prevented.

50 In practice, it has been found that the delivery of the webs of paper to the pair of separate paper-feeding means is very greatly improved if the paper necessary for the feeding operation is previously withdrawn from the rolls. One means 55 for accomplishing this result is shown in Figs. 1, 22, 33 and 34, wherein it will be noted that upper and lower draw bars 153 and 154 are provided for the pair of paper rolls 145 and 146, respectively, these draw bars being provided with 60 rollers 154a. The upper draw bar 153 may be mounted at its opposite ends on arms 155 constituting integral extensions of a sleeve 156. The sleeve 156 is loosely mounted on a horizontal rock shaft 157 extending across the rear of the machine and supported in suitable bearings provided by brackets 158. The lower draw bar 154 is similarly supported at its ends on arms 159 constituting integral extension of a sleeve 161 loosely mounted on a rock shaft 162 extending across the machine parallel to the rock shaft 157 and journaled in bearings provided by the supporting brackets 158. The arms 155 and 159 may be provided with adjustable counter-weights 162a and 65 163a, respectively, whereby the tension of the

draw bars 153 and 154 on the paper may be controlled.

As shown in Fig. 33, the web of paper from the upper roll 145 first passes under the upper draw bar 153, and then over a guiding bar 163 and around a second guiding bar 164. From here the paper passes vertically over an upper guiding bar 165 to the right hand paper-feeding means of the pair. The web of paper from the lower roll 146 similarly passes under the lower draw bar 154, and then over a guiding bar 166 and around a guiding bar 167. From here the paper passes vertically over an upper guide bar 168 to the right hand paper-feeding means. In order to operate draw bars 153 and 154 downwardly together so as to draw supplies of paper from their respective rolls suitable means are herein provided, the same being shown as comprising pairs of arms 169 and 171, which are rigidly secured to the rock shafts 157 and 162, 95 respectively, and which are interconnected by means of a pair of links 172. The upper pair of arms 169 abut against pins 173 on the adjacent arms 155, respectively, when the upper draw bar 153 is to be lowered, while the lower pair of arms 171 abut against pins 174 on the adjacent arms 159, respectively, when the lower draw bar 154 is to be lowered.*

The pair of paper rolls 147 and 148 associated with the left hand paper-feeding means of the 105 pair are provided with upper and lower counterbalanced draw bars 175 and 176, respectively, which are mounted similarly to the pair of draw bars 153 and 154 and actuated by the rock shafts 157 and 162 through similar linkage 177. Thus, 110 the two pairs of draw bars 153, 154 and 175, 176 may be simultaneously actuated downwardly to draw the desired supplies of paper from their respective paper rolls, upon the actuation of one of the rock shafts, say, for example, the upper 115 shaft 157. This rock shaft may be conveniently actuated by means of a crank arm 178 which is connected by a link 179 to a point 181 on a rotatable gear-wheel 182 (Fig. 29). The gear-wheel 182 is actuated by a gear-wheel 183 mounted on the right hand end of a cam shaft 184. The cam shaft 184 extends across the rear of the machine and is connected by bevel gear-wheels 185 to the cross shaft 81.

In the operation of the apparatus just-described, the rotation of the gear-wheel 182 causes the reciprocation of the link 179. When the link 179 is actuated downwardly, the crank arms 169 and 171 engage the pins 173 and 174 to cause the downward movement of the draw bars 153 and 154, respectively, the parts finally assuming at the end of the stroke the dotted-line position shown in Fig. 33, wherein it will be noted that a supply of paper has been withdrawn from the rolls 145 and 146. A similar supply of paper (not shown) has also been withdrawn from the other pair of rolls 147 and 148 due to the simultaneous operation of the draw bars 175 and 176. When the link 179 is raised, as a result of the continued turning of the gear-wheel 182, the lost-motion connection obtaining between the crank arms 169 and 171 and the draw-bar arms 155 and 159, respectively, permits the upward movement of said crank arms independently of said draw-bar arms. The same operation occurs 145 in connection with the other pair of draw bars 175 and 176. It is noted that the downward movement of the several draw bars occurs prior to the operation of the paper-feeding means.

Considering next the pair of separate paper- 150

feeding means, which are shown in Figs. 21 and 22 as being positioned in side-by-side relation at the rear of the machine, the right hand one of the pair only will be described in detail, inasmuch as the other is identical in construction therewith. As shown in Fig. 27, the right hand paper-feeding means conveniently comprises a lower pair of feeding rolls 186 and 187 and an upper pair of feeding rolls 188 and 189. The supporting roll 187 of the lower pair is suitably supported at its opposite ends by a pair of vertical side plates 191 mounted on the table 3, as will presently appear. The upper pressure roll 186 of the lower pair is conveniently mounted at its opposite ends on a pair of arms 192 pivotally mounted on studs 193 carried by the side plates 191. As shown in Fig. 29, an outer end of each of the pivoted arms 192 is provided with a bolt 194, the lower end of which is adapted to rest upon an adjacent supporting shoulder 195.

The upper roll 186, which may have a resilient covering, such as rubber or felt, is preferably pressed toward the lower roll 187 by spring means in order that proper contact may be obtained with the web of paper passing between the two rolls. To this end, a pair of arms 196 are conveniently mounted on the side plates 191 for movement in a horizontal plane and are provided with spring-pressed plungers 197. When the arms 196 are in the position shown in the drawings, these plungers engage the upper side of the arms 192 so that the desired frictional contact is obtained with the web of paper passing between the rolls. The pressure, however, may be easily removed by swinging inwardly the arms 196, so that the spring-pressed plungers 197 are moved out of their position directly over the arms 192. The roll 189 of the upper pair of feeding rolls is supported similarly to the roll 187 of the lower pair on a pair of side plates 198. These side plates are positioned in alignment with the side plates 191 and directly to the rear of same. The upper pressure roll 188 is similarly engaged by spring-pressed plungers 199 carried by a pair of pivoted supporting arms 200, which engage the spaced crank arms of a rock shaft 201 extending between the side plates 198 and suitably journaled therein as illustrated in Fig. 21.

The lower pair of feeding rolls 186 and 187 may extend into a passage 202 for the web of paper passing from the upper paper roll 145. This passage is formed by a pair of spaced plates 203 and 204 suitably supported in the vertical side plates 191, as illustrated in Fig. 27. The lower plate 204 may be mounted at its rear edge on a bar 205 which also extends between the vertical side plates 191 and affords a curved guiding surface 206 for the web of paper as it enters the passage 202. The web of paper is further guided as it moves toward the passage 202 by means of an inclined plate 207, which extends downwardly from the guiding bar 205 between the rear pair of side plates 198 in the direction of the guiding bar 165 for the web of paper passing from the upper roll 145.

The upper pair of rolls 188 and 189 similarly extend into a passage 208 for the web of paper passing from the lower paper roll 146. This passage is formed by a pair of upper and lower plates 209 and 210 which are suitably supported in spaced relation between the vertical side plates 191 and 198, as shown in Fig. 27. The rear edge of the lower plate 210 is supported on a guide bar 211, similar to the lower guide bar 205. The bar 211 also supports an upper edge of an in-

clined guide plate 212 which extends downwardly over the guide plate 207 in the direction of the guide bar 168 for the lower paper roll 146, whereby the web of paper may be suitably guided in its movement from the paper roll 146 through the upper pair of feeding rolls 188 and 189. A weighted roll 213 may be suitably mounted, as shown in Fig. 27, in engagement with the web of paper passing over the guide plate 212, whereby the web of paper may be prevented from slipping backwardly during the operation of the draw bar 154 in the event that the upper pair of feeding rolls 188 and 189 are rendered ineffective, all as will presently appear hereinafter.

The front portions of the pair of spaced plates 209 and 210 are curved downwardly, so that the outlet opening of the passage 208 is positioned directly above the outlet opening of the lower passage 202. Thus, the webs of paper passing through the passages 202 and 208 are positioned in superposed relation at the outlet openings thereof. It will be noted that the left hand paper-feeding means, which is positioned in side-by-side relation to the paper-feeding means under description, is similarly provided with lower and upper pairs of feeding rolls 214 and 215 for respectively actuating webs of paper from the pair of rolls 147 and 148 through passages, the outlet openings of which are positioned in superposed relation, so that the webs of paper passing therethrough may also be superposed.

Considering next the means for actuating the paper-feeding rolls, as shown in Figs. 22, 23, 24, 27, 29, 30, 31 and 32, the main cam shaft 184, which is so actuated by the cross shaft 81 as to make two revolutions for each complete reciprocation of the traverse bar 55, is provided with a gear-wheel 216 which is positioned between the supporting side plates of the pairs of separate paper-feeding means. The gear-wheel 216 meshes with a gear-wheel 217 which is mounted on a shaft 218 suitably journaled on the underside of the table 3. The right hand end of the shaft 218 extends beyond the adjacent side plate 191 and is provided with a cam 219 having a cam groove 221 for a cam roller 222, as shown in Fig. 29. The cam roller 222 is mounted on a gear-wheel sector 223 pivotally supported at 224 on the table 3. The gear-wheel sector 223 meshes with a gear-wheel 225, which is loosely mounted on a projecting end portion 226 of a shaft 227 upon which the lower feed roll 187 is loosely mounted, as illustrated in Fig. 32.

The gear-wheel 225 has rigidly secured thereto an arm 228 which carries a spring-pressed pawl 229 adapted to co-act with a ratchet-wheel 231 rigidly secured to the shaft end portion 226. A change gear train 232 extends between a gear-wheel 233 rigidly secured to the shaft end portion 226 and a gear-wheel 234 rigidly secured to an adjacent end of the lower supporting feed roll 187. An opposite end is provided with a gear-wheel 234a which is connected by a gear train 235 to a gear-wheel 236 mounted on the left hand end of the feeding roll 189 of the upper pair. The gear-wheel 236 also meshes with a gear-wheel 237 rigidly secured to the pressure roll 188, whereby the upper pair of rolls 188 and 189 may be simultaneously actuated. The lower pair of rolls 186 and 187 are also simultaneously actuated by means of the gear-wheel 234a which meshes with a gear-wheel 238 mounted on the left hand end of the feed roll 186, as shown in Fig. 22. The remaining pairs of feed rolls 214 and 215 are similarly geared together and

are driven from a shaft 241 which extends through adjacent vertical side plates and carries a gear-wheel 242 positioned to mesh with the gear-wheel 234a secured to the roll 187.

5 In the operation of the machine, as the diameter of the coil under construction on the spindle 34 increases, it is desirable to increase progressively the length of the sheets of winding material, whereby sheets of sufficient length to extend 10 tend at least once around the coils may be continuously supplied throughout the operation of the machine. One simple means for accomplishing this desired result is shown in Figs. 29 to 32, inclusive, wherein a ratchet-wheel 243 is 15 loosely mounted on the shaft end portion 226 between the ratchet-wheel 231 and the gear-wheel 233. A spring 244 tends to actuate the ratchet-wheel 243, so that a lug 245 thereon engages an abutment 246 adjustably mounted 20 at 247 on the vertical side plate 191. The ratchet-wheel 243 is also provided with an arcuate cam portion 248, which is so positioned on the ratchet-wheel 243 that a front edge thereof is disposed immediately adjacent to the lug 245. The cam 25 portion 248 is also positioned immediately adjacent to the ratchet-wheel 231, with an outer surface 249 thereof disposed just beyond the periphery of the ratchet-wheel 231. The spring-pressed pawl 229 if of sufficient width to extend 30 beyond the side of the ratchet-wheel 231 and engage the outer surface 249 of the cam portion 248, at which time the pawl 229 is disengaged from the ratchet-wheel 231.

When the parts are in the position shown in 35 Fig. 29, wherein the lug 245 is in engagement with the abutment 246 and the pawl 229 is at one end of its stroke and in engagement with the cam surface 249, the counter-clockwise rotation of the cam 221 causes a similar movement 40 of the pawl 229, through the gear sector 223, the gear-wheel 225 and the arm 228 secured thereto. Since the pawl 229 is now riding over the cam surface 249, it is disengaged from the ratchet-wheel 231 until it reaches the front edge 45 of the cam surface 249 at the abutment 246. The continued movement of the arm 228 with its pawl 229 now causes the actuation of the ratchet-wheel 231 until the arm 228 has reached the other end of its stroke, which may conveniently be determined by an adjustable abutment 251 positioned 50 in the path of travel of the pawl 229 and suitably supported at 252 on the adjacent side plate 191. The movement of the ratchet-wheel 231, which has occurred during the travel of the pawl 229 from the front edge of the cam-surface 55 249 to the abutment 251, through the gear mechanism previously described, causes the turning of the lower and upper pairs of feed rolls 186, 187 and 188, 189, respectively. As a result, the supplies of paper previously withdrawn from the pair 60 of rolls 145 and 146 by the draw bars 153 and 154 are fed through the passages 202 and 208, respectively, passing from the outlet openings thereof in superposed relation. At the same time, the other pair of feed rolls 214 and 215 operate 65 to feed forwardly the supplies of paper previously withdrawn from their paper rolls 147 and 148. It will be noted that when the cam portion 248 is in the position just-described, the amount of paper fed forwardly is a minimum, and this may be adjusted within small limits by properly moving the abutments 246 or 251.

In accordance with the present invention, the period during which the pawl 229 is in engagement with the ratchet-wheel 231 is progressively

increased throughout the operation of the machine, in order to increase the amount of paper fed by the rolls. To this end, means are provided for automatically stepping backwardly the ratchet-wheel 243 with its cam 248 from the position shown in Figs. 29 and 30. Conveniently, said means may comprise a horizontal spring-pressed lever 253, which is pivoted at 254, so that a lower edge is in operative relation to a cam abutment 255 on an adjacent portion of the cam shaft 184. The arrangement is such that the lever 253 is moved vertically once for each revolution of this cam shaft. A spring-pressed pawl 256 may be mounted on the outer end of the lever 253 so as to engage the ratchet-wheel 243 and advance the same, say one tooth for each revolution of the cam shaft 184. A pawl 257 is provided for holding the ratchet-wheel 243 in its advanced position against the force of the spring 244, when the actuating pawl 256 is returning from an advanced position.

The holding pawl 257 preferably has an elongated slot 258 adapted to receive a pin 261 extending from the actuating pawl 256. The length of the slot 258 is such that the pawl 256 may be reciprocated by the actuating lever 253 without affecting the holding pawl 257. The pawl 257 is provided with an arm 262, which engages one arm of a bell-crank lever 263, an opposite arm of which is connected by a rod 264 to the rock shaft 52, shown in Fig. 12. The arrangement is such that when the rock shaft 52 is moved in a counter-clockwise direction, due to a downward force on a push button 265 carried by the arm 47 of the bell-crank lever 48 shown in Fig. 11, 110 a similar force is exerted on the arm 262 of the holding pawl 257. As a result, the pawl 257 is actuated out of engagement with the ratchet-wheel 243 as well as the actuating pawl 256. The ratchet-wheel 243 is now actuated under 105 the force of the spring 244 until the lug 245 engages the abutment 246. The cam 248 is now in its original starting position. It will thus be seen that each of the pair of separate paper-feeding means intermittently feed forwardly 120 therefrom progressively increasing lengths of superposed webs, throughout the entire operation of the machine.

Coming next to the pair of separate paper-severing means shown in Figs. 21, 23, 24, 27 and 28, since these separate means are identical in construction, the right hand one only will be described in detail. It will be observed that this paper-severing means comprises a knife frame 266 of rectangular-like form, the opposite side 130 edges of which are slidably mounted in a pair of guide ways 267 conveniently formed by a pair of guide plates 268 mounted on the front edges of the vertical side plates 191. A knife 269 may be conveniently mounted on an upper front-surface portion of the knife frame 266 so as to co-operate with a knife 271 which is suitably mounted just below the outlet openings of the paper-supply passages 202 and 208, respectively. The co-operating edges of the knives 269 and 271 140 are normally spaced, as shown in Fig. 27, so as to permit the webs of paper to pass therebetween from the passages 202 and 208 under the feeding action of the pairs of rolls 186, 187 and 188, 189.

The knife frame 266 may be reciprocated in its 145 guide ways 267 by any appropriate means. A preferred means shown in Figs. 27 and 28 comprises a rock shaft 272 which is suitably supported just to the rear of the main cam shaft 184. This rock shaft is provided with a pair of intermediate 150

crank arms 273 and 274 which respectively engage cams 275 and 276 mounted on the main cam shaft 184. The rock shaft 272 is also provided with a pair of end crank arms 277 which engage 5 a lower edge 278 of the knife frame 266 immediately adjacent to the guide ways 267. An intermediate crank arm 279 also extends from the rock shaft 272 into a recess 281 formed in the lower portion of knife frame 266. The cams 275 10 and 276 are so designed that the cam 275 through the crank arm 273 and the end crank arms 277 causes the knife frame 266 to be supported in the raised position shown in Fig. 27 except during the cutting period. During this period, the cam 15 276 operates through the crank arms 274 and 279 to lower the knife frame 266, thereby causing the severing of sheets of paper from the superposed webs which have been passed between the knives 269 and 271 from the passages 202 and 208. Upon 20 the completion of the severing operation, the cam 275 causes the knife frame 266 to be raised into its upper position and there supported until the next cutting operation. It is noted that the reciprocation of the knife frame 266 just-described 25 conveniently occurs immediately following the operation of the pairs of feed rolls 186, 187 and 188, 189. The left hand paper-severing means similarly comprises a reciprocal frame 282, which is positioned directly in front of the co-operating 30 paper-feeding means, whereby severed sheets formed of a plurality of layers of windable material may be obtained simultaneously with the sheets formed by the reciprocation of the knife frame 266.

35 Coming next to the common transfer means whereby the severed sheets of paper may be delivered to the winding spindle 34, as shown in Figs. 13, 14, 15, 21, 25, 26 and 27, said means preferably comprises the angularly-adjustable frame 57 and a reciprocatory carriage 283 provided with sheet-engaging fingers 284. The angularly-adjustable frame 57 conveniently comprises a pair of sheet-supporting plates 285 and 286 which are positioned in spaced side-by-side 40 relation directly in front of the pair of knife frames 266 and 282, respectively. The rear edges of the plates 285 and 286 may be supported on a cross member 287 conveniently hinged at 288 on the vertical side plates 191, as illustrated in 45 Fig. 27. The front edges of the plates 285 and 286 may be mounted on a cross member 289, as shown in Fig. 14. The cross member 289 is provided with a vertical pedestal 291 which engages the table 3 when the sheet-transfer frame 57 is in 50 its lower position. As shown particularly in Figs. 25 and 26, the maximum upper position of the frame 57 may be controlled by means of a nut 292 which is adjustably mounted on a threaded end portion 293 of the pedestal 291 extending 55 through the table 3.

60 The right hand sheet-supporting plate 285 preferably is provided with a plurality of paper-guiding strips 294 which extend the full length thereof. The rear ends of these strips are mounted 65 on the upper side of a cross strip 295 which is suitably supported at the rear edge of the plate 285 in such spaced relation thereto as to receive therebetween the webs of paper as they pass from the passages 202 and 208 through the knife frame 266. As illustrated in Fig. 14, the front ends of the strips 294 are similarly supported on 70 a cross strip 296 which is also suitably supported in spaced relation to the adjacent surface of the plate 285, so that the superposed sheets may pass

therebetween. In operation, the longitudinal strips 294 tend to prevent the severed sheets of paper from wrinkling, as well as guiding the same, during the movement over the surface of the sheet-supporting plate 285 toward the winding spindle 34. The front edge of the plate 285 and the adjacent edge portion of the cross strip 296 are preferably so formed that the advancing edge of the sheets is curved downwardly, thereby further assuring that the sheets of paper about to be injected into the coils are smooth and free from irregularities, as well as parallel to the longitudinal axis of the spindle 34.

80 The reciprocatory carriage 283 and the sheet-engaging fingers 284 are illustrated in Figs. 14, 15, 21, 23, 24 and 25. The carriage 283 preferably comprises an elongated member 297, which extends across the width of the machine, and is provided with a central bearing 298 adapted to receive a guide rod 299. This rod is positioned 85 between the sheet-supporting plates 285 and 286, and is suitably supported on the angularly adjustable frame 57 at 301 and 302. The guide rod 299 extends rearwardly from the bearing 302 between the pair of separate paper-feeding means, 90 providing a bearing for a tail portion 303 of the elongated cross member 297. The opposite ends of the cross member 297 are provided with guiding rollers 304 which respectively engage rods 305 suitably supported at the side edges of the angularly-adjustable frame 57.

95 The carriage 283 may be reciprocated over the angularly-adjustable frame 57 by means, such, for example, as are shown in Fig. 25, wherein a cam 306 is mounted on the shaft 218 directly below the guide bar 299 and the tail portion 303 of the carriage 283. The cam 306 may be provided with a cam groove 307 for a roller 308 which is mounted on a gear-wheel sector 309 positioned to mesh with a gear-wheel sector 311 pivotally 105 mounted at 312. An arm 313 is secured to the gear-wheel sector 311 and extends upwardly between the webs of paper passing from the supply rolls to a link 314. This link is pivotally mounted, as shown in Fig. 21, on a rod 315 which is adjustably secured to a block 316. The said block 110 is pivotally supported at 317 on the tail portion 303 of the carriage 283 just to the rear of the central bearing 298. The cam 306 is so designed 115 as to cause a forward movement of the carriage 283 subsequent to the operation of the paper-severing means and just before the traverse bar 55 reaches the end of its stroke, so that the severed sheets of paper may be supplied to the spindle 34 at the proper instant. The cam 306 also 120 causes the return of the carriage 283 to the starting position shown in Fig. 21 prior to the operation of the paper-feeding rolls.

125 Referring to the sheet-engaging fingers 284 shown in detail in Figs. 14 and 15, as therein illustrated, each of the fingers 284 is provided with a friction strip 318 which is adapted to engage frictionally a sheet of paper. The friction strip 318 may be supported on an outer end of an arm 319, which is loosely mounted on a rock shaft 321 extending across the width of the sheet-supporting plate 285 and suitably supported at its ends on the adjacent portion of the carriage 283. The mounting of the arm 319 on the rock shaft 321 is such that the finger 284 is movable 130 about a horizontal axis as well as a vertical axis, thereby causing the sheets of paper to be fed more positively and with less tendency for wrinkling. Conveniently, adjustable spring-tension means 322 is secured to the arm 319, whereby the 135

frictional engagement of the finger 284 with the sheets of paper may be controlled. The arm 319 is provided with an adjustable abutment 323 which engages a shoulder 324 extending from the 5 rock shaft 321, for reasons as will presently appear.

Should the pressure of the fingers 284 on the sheets of paper, while said sheets are being wound on the spindle, tend to prevent the proper winding thereof, the fingers 284 are conveniently replaced as illustrated at the left hand portion of the carriage 283, with a sheet-engaging roll 325 which is loosely mounted on a shaft 326 carried by a pair of spring-pressed arms 327, as shown in 10 Fig. 21. The roll 325 carries a ratchet-wheel 328, which co-operates with a pawl 329 mounted on one of the arms 327,—the arrangement being such that, when the carriage 283 is moved forwardly, the pawl 329 prevents the turning of the 15 roll 325 as it grips frictionally the severed sheets of paper and moves the same in the direction of the winding spindle 34. When the severed sheets of paper are finally injected into the coil, however, the pawl-and-ratchet mechanism 328, 329 permits the turning of the roll 325 by the advancing sheets of paper, so that the retarding force is a minimum. The spring-pressed arms 327 conveniently have a lost-motion connection 20 with a supporting rock shaft 330, similar to the lost-motion connection 323, 324 between the 25 spring-pressed fingers 284 and the rock shaft 321.

The gradual increase in the diameter of the coils as they are built up on the spindle 34 necessitates severed winding sheets of progressively 30 increasing length, and means have been previously described for accomplishing this desired result. Now will be described preferred means for 35 automatically adjusting the sheet-transfer means in accordance with the increase in length of the sheets of paper supplied thereto. The said preferred means is shown in Figs. 21, 22, 23, 24 and 40 25 and comprises an elongated cam bar 331. This cam bar is conveniently mounted on the angularly-adjustable frame 57 intermediate the sheet-supporting plates 285 and 286 for reciprocatory movement between the front and rear of the machine. Means are herein provided for exerting a 45 force on the cam bar 331 normally tending to move it rearwardly from the front of the machine into 50 the starting position shown in Fig. 25, which is the position assumed for the shortest sheet to be fed, said means being illustrated as a weight 332 supported on a flexible element 333. The element 333 passes at its upper end around a guiding 55 roller 334, which is supported on the angularly-adjustable frame 57, and is secured to the front end of the cam bar 331.

Means are also provided for intermittently advancing the cam bar 331 forwardly from the starting position shown in Fig. 25, in accordance with the increase in length of the sheets of paper supplied to the angularly-adjustable frame 57. Said means may conveniently comprise a spring-tensioned lever 335 which is pivoted at 336 so as to 60 engage normally a cam 337. The cam 337 is mounted on the main-cam shaft 184 and is provided with an actuating shoulder 338. The lever 335 carries a pawl 339, one end of which is adapted to co-act with a rack 341 formed on the under-side of the cam bar 331. The pawl 339 is provided with a beveled surface 342 which co-acts with a pin 343. A spring 344, which extends between a tail end of the pawl 339 to the lever 335, causes the cam surface 342 of the pawl 339 to engage 65 the pin 343. In operation, as the lever 335 is en-

gaged by the actuating shoulder 338, it is moved forwardly, carrying with it the pawl 339. The pawl 339, however, is not only moved forwardly but also vertically under the action of the spring 344 into engagement with the rack 341, with the result that the cam bar 331 is moved forwardly. This movement occurs once for each revolution of the cam shaft 184 and is preferably timed to occur just prior to the forward movement of the carriage 283.

As shown in Fig. 21, the cam bar 331 co-acts with a pair of rollers 345 respectively carried by crank arms 346 and 347 mounted on the adjacent ends of the rock shafts 321 and 330,—the arrangement being such that, when the arms 346 and 347 are raised due to the engagement of their rollers with the cam bar 331, the spring-pressed fingers 284 and the spring-pressed roll 325 are actuated out of engagement with the severed sheets of paper on the supporting plates 285 and 286, respectively. Figs. 21 and 25 show the spring-pressed fingers 284 and roll 325 in such raised position, permitting the feeding of the webs of paper thereunder. When the carriage 283 is moved forwardly, the rollers 345 of the crank arms 346 and 347 are almost immediately disengaged from the cam bar 331, with the result that the fingers 284 and the roll 325 frictionally engage the severed sheets of paper on the sheet-supporting plates 285 and 286, respectively, causing said sheets to be moved forwardly to the winding spindle 34. Thus, the sheets of paper are fed forwardly for substantially the full stroke of the carriage 283 which is the required condition when said sheets are of minimum length.

Upon the return movement of the carriage 283, the friction fingers 284 and roll 325 are again moved into their elevated positions by the cam bar 331. Prior to the next forward movement of the carriage 283, the actuating shoulder 338 of the cam 337 causes the pawl 339 to move the cam bar 331 forwardly one step, in which position it is held by a spring-pressed holding pawl 348. As a result, when the carriage 283 is again moved forwardly on its feeding stroke, the spring-pressed fingers 284 and roll 325 are moved forwardly a greater distance before engaging the severed sheets of paper, and, therefore, have a correspondingly shorter feeding stroke. In this manner, the feeding stroke of the carriage 283 is automatically decreased as the length of the severed sheets is increased. When the cam bar 331 has been moved forwardly the desired extent, so that severed sheets of maximum length may be properly delivered to the winding spindle 34, the cam bar 331 may be returned to its initial starting position merely by actuating the releasing pawl 348. The actuation of the releasing pawl 348 may be effected simultaneously with the actuation of the pawl 257 associated with the paper-feeding means and the actuation of the locking lever 42 associated with the tail stock, by means of a rod 349 and a crank 351 rigidly secured to the rock shaft 52 shown in Fig. 12.

Proceeding with the description of the machine, 140 means are provided, whereby the sheet-transfer frame 57 may be angularly adjusted in accordance with the increase in diameter of the coils under formation on the winding spindle 34. Such means are shown in Figs. 4, 7, 8, 25 and 26 145 as comprising a bell-crank lever 352 which is loosely mounted on a shaft 353 suitably supported in the winding head 6 of the machine. One arm of the bell-crank lever 352 carries a spring-pressed pawl 354 which co-acts with a ratchet- 150

wheel 355 rigidly secured to the shaft 353. The bell-crank lever 352 is so tensioned that the other arm thereof normally engages an adjacent cam, which is mounted on the cross shaft 81 and provided with an actuating shoulder 356. Thus, for each rotation of the cross shaft 81, the ratchet-wheel 355 is advanced one tooth, thereby causing the turning of the shaft 353. A spring-tensioned holding pawl 357 is also provided and it has a tall portion 358, which is positioned immediately adjacent to a tall portion 359 of the actuating pawl 354, so that when the holding pawl 357 is moved into its ineffective position, the actuating pawl 354 is similarly rendered ineffective. The holding pawl 357 may be connected by a bell-crank lever 360 and a rod 361 to a crank arm 362 on the rock shaft 52, as shown in Fig. 12.

The shaft 353 is connected by reversible worm-and-wheel mechanism 363 to a shaft 364 which carries a gear-wheel 365 on its outer end. The gear-wheel 365 meshes with a gear-wheel 366 supported on one end of a shaft 367 which is suitably mounted on the front edge of the machine and which terminates in a crank arm 368. The crank arm 368 has an arm 369 adjustably secured to an outer surface thereof by means of a bolt 371. Preferably, the crank arm 368 is provided with a slot 372 of T-shape, which extends the length thereof, and the arm 369 is also provided with a slot 373. The bolt 371 conveniently has one end portion interlocked with the slot 372, while the other end portion extends through the slot 373 and is provided with a nut 374. Thus, the bolt 371 may be moved to a desired adjusted position in the slots 372 and 373 of the arms 368 and 369, respectively, and said arms then rigidly clamped together by tightening the nut 374. The arm 369 carries a vertically adjustable rod 375 which extends into a recess 376 in the underside 40 of the cross member 289 about midway between the ends thereof. The weight of the angularly-adjustable frame 57 may be counter balanced by means of a weight 376. This weight is carried by a flexible element 377 which extends around a pulley-wheel 378 mounted on the upper side of the table 3 and which is secured to the arm 369. Conveniently, the angularly-adjustable frame 57 may be actuated manually by means of a foot pedal 379 which is connected by a flexible element 381 to the weight 376.

When the machine is operated, the bell-crank lever 352 is reciprocated once for each revolution of the cross shaft 81, causing the actuating pawl 354 to advance the ratchet-wheel 355 step-by-step and thereby effect the turning of the shaft 353. The turning of the shaft 353 through the arms 368 and 369 causes the vertical movement of the supporting rod 375 and hence the raising of the angularly-adjustable frame 57. Such movement occurs automatically throughout the operation of the machine, so that the front edge of the angularly-adjustable frame 57 is maintained in desired spaced relation to the coils under formation as the diameter thereof increases. When it is desired to return the angularly-adjustable frame 57 to its original starting position, it is necessary only to depress the holding pawl 357 sufficiently to cause the release of the actuating pawl 354. Since the worm-wheel mechanism 363 is reversible, the angularly-adjustable frame 57 now drops under its own weight to the starting position.

In the operation of the machine thus far described, the winding material supplied to the spindle 34 is in the form of superposed sheets.

The invention contemplates means, however, whereby single- and multiple-layer sheets may be supplied to the winding spindle 34 at any desired period and for any desired time interval during the formation of the coils. The preferred means for accomplishing this desired result is shown in Figs. 21, 23, 24, 25, 27 and 36 to 40, inclusive. Referring first to Figs. 21, 24 and 25, it will be observed that the adjacent ends of the rock shaft 201, which is connected by its crank arms to the upper pressure roll 188, and a rock shaft 382, which is similarly connected to the corresponding pressure roll of the adjacent upper pair of feed rolls 215, are respectively provided with crank arms 383 and 384, which extend downwardly and forwardly between the adjacent vertical side plates 198 of the pair of separate paper-feeding means. These arms are provided with shoulders 386 which are respectively positioned in operative relation to pivoted vertical arms 387 and 388 connected to move together. An arm 388a is connected to one of the arms 387 and 388, say the latter. This arm is adapted to co-act with a cam 389 mounted on the main cam shaft 184. The cam 389 is designed to cause the rocking of the arm 388a once for each revolution of the cam shaft 184, and this movement is imparted by the vertical arms 387 and 388 to the crank arms 383 and 384. The extent of movement of said crank arms is such that the upper pressure rolls are raised into an ineffective position without interrupting the geared connection with their co-operating lower driving rolls. Thus, the upper pairs of feed rolls associated respectively with the right and left hand paper-feeding means are periodically rendered ineffective for a relatively short period without interrupting the operation of the lower pairs of feed rolls.

In order to maintain the upper pairs of feed rolls 188-189 and 215 ineffective over a period of time which is greater than that due to the cam 389, so that single layer sheets may be successively supplied to the sheet-transfer means for delivery to the winding spindle 34, means are provided for holding the crank arms 383 and 384 in their raised position. In the present instance, said means are shown as comprising a pair of connected spring-pressed levers 391 which tend normally to move upwardly, so that notches 392 therein are in a position to receive shoulders 393 on the crank arms 383 and 384, respectively. Preferably, the pair of spring-pressed levers 391 are rigidly secured to an armature 394 of an electro-magnet 395, so that, when the electro-magnet 395 is energized, the armature 394 causes a downward movement of the pair of levers 391 against the force of their spring and hence the disengagement of the shoulders 393 from the recesses 392. The crank arms 383 and 384 then drop and with them the raised feed rolls, with the result that the upper pairs of feed rolls 188-189 and 215 are now in position to feed webs of paper in the direction of their severing means.

The energizing circuit (not shown) for the electro-magnet 395 may be automatically controlled as shown in Figs. 35 to 38, inclusive, wherein it will be noted that a switch 396 is provided with a movable element 397 which is pivotally mounted at 398 on a vertical plate 399 and which is normally actuated by means of a spring 401 into engagement with a stationary element 402 of the switch 396. Trip means for the movable switch element 397 is provided which may take the form of a pivoted lever 403. The lever 403

may be tensioned by means of a spring 404, so that an arm 405 of the lever 403 normally engages a pin 406 on the movable switch element 397 to hold the same in its open position shown in Fig. 38. The actuation of the movable switch element 397 into its open position, as well as the actuation of the trip means 403 into its ineffective switch-releasing position is effected preferably by means of pawl-and-ratchet mechanism. As shown in Figs. 35 and 37, this mechanism comprises a lever 407, which is positioned to be actuated by a pair of pins 408 carried by a collar mounted on the cross shaft 81. The lever 407 carries a spring-pressed pawl 409 which co-operates with a ratchet-wheel 411, movement of which is resisted by a coil spring 412. A holding pawl 413 is provided which is connected by linkage 414 to the rock shaft 52 shown in Fig. 12. The actuating pawl 409 is provided with a projecting portion 415, which is positioned directly under the holding pawl 413, so that, when the pawl 413 is moved into its ineffective position, the pawl 409 is actuated thereby into its ineffective position, permitting the ratchet-wheel 411 to return to the starting position shown in Fig. 35 under the force of the spring 412.

The ratchet-wheel 411 may be provided with a front plate 416 upon which is mounted a shoulder 417 which rests upon an adjustable abutment 418 in the form of a screw member when the ratchet-wheel 411 is in its starting position. The shoulder 417 is adapted to co-operate with a lever 419 which is actuated by means of a spring 421 so as to engage normally an abutment 422 on the movable switch element 397. When the shoulder 417 is actuated into engagement with the free end of the lever 419 by the pawl-and-ratchet mechanism 409, 411, the movable switch element 397 is actuated out of engagement with the co-acting stationary element 402 into the position shown in Fig. 38, whereupon the energizing circuit for the electro-magnet 395 is interrupted. Such interruption results in the upward movement of the lever arm 391 under the force of its spring. The subsequent raising of the crank arms 383 and 384 by the cam 389 permits the shoulder 393 to drop into the recess 392 in the lever 391, so that the upper pairs of feed rolls 188-189 and 215 are rendered ineffective. It will thus be seen that superposed sheets of paper may be obtained at the beginning of the operation of the machine and while the shoulder 417 is moving between the abutment 418 and the lever 419 mounted on the movable switch element 397. If the abutment 418 is lowered, the interval during which the switch 396 remains closed is increased, and hence the feeding period of the upper pairs of feed rolls 188-189 and 215 is lengthened. The raising of the abutment 418, however, causes a decrease in the feeding period of these rolls. One possible adjustment is that shown in the drawings, wherein the upper pairs of feed rolls 188-189 and 215 are rendered effective sufficiently long, so that multi-layer sheets may be provided for injection into the coils under formation on the spindle between the first and second layers of wire only.

Conveniently, the tripping lever 403 may be actuated, when multiple-layer winding material is again to be supplied to the coils, by means of an arm 423 adjustably mounted on a shaft 424 to which the ratchet-wheel 411 is secured. The arm 423 co-acts with an arm 425 of the tripping lever 403, engaging the same when the coils have been wound to the point at which multiple-layer

winding material is again to be supplied thereto. This point is determined by properly adjusting the arm 423 on the supporting shaft 424. When the arm 423 engages the arm 425 of the trip lever 403, as shown in Fig. 38, the arm 405 of the trip lever is actuated out of engagement with the shoulder 406, permitting the movable switch element 397 to return under the force of the spring 401 to the circuit-closing position. The closing of the switch 396 results in the energization of the electro-magnet 395, causing the dropping of the levers 391 and, consequently, the movement of the upper feed rolls into their effective position. Multi-layer sheets are now supplied to the winding spindle 34 so long as the machine continues to operate,—this being automatically controlled by the counter mechanism shown in Fig. 4, which causes the actuation of the switch member 14 into its circuit-opening position, and hence the de-energizing of the driving motor 1, when the formation of the coils has been completed. One such completed coil is illustrated in Fig. 42, wherein it will be observed that multiple-layer windings have been supplied to the coil at the beginning and ending thereof, and that single-layer sheets 427 only have been supplied to the intermediate portions. Such type of coil is particularly adaptable for use in ignition circuits, wherein the electrical conditions are such that additional insulation is desirable for the inner 105 and outer layers of the coil.

Figs. 39 and 40 illustrate alternative control means for the electro-magnet 395, comprising pawl-and-ratchet mechanism which is identical in construction with that shown in Fig. 35. The added feature is embodied in the following means which includes a switch arm 428 rigidly secured to the ratchet-wheel and provided with a pair of electrically connected spring contact fingers 429 and 431. These contact fingers are adapted to co-act, respectively, with inner and outer circular series of pins 432 and 433, the length of said fingers being such that contact of finger 429 with a pin 432 in the inner series is immediately followed by contact of finger 431 with a pin 433 in the outer series, and so on throughout the complete angular movement of the arm 428. Each of the pins is conveniently supported in an abutment 434 having a set screw 435, so that the pins may be moved into and out of co-operative relation with the fingers 429 and 431. The abutments 434 are suitably supported on a vertical plate 436. This plate is insulatedly mounted on a main supporting structure 437 which carries a spring contact finger 438 adapted to co-act with a contact member 439 movable with the switch arm 428 and electrically connected thereto. The insulated vertical plate 436 and the contact member 439 are connected in the energizing circuit of the electro-magnet 395, so that the latter is energized only when one or the other of the contact fingers engages a co-operating pin. Since the number of pins is equal to the largest number of coil layers, it follows that the number of multiple-layer windings is dependent upon the number of pins 432 and 433 which are positioned in the path of travel of the contact fingers 429 and 431, respectively.

Should it be desirable to provide multiple-layer winding material throughout the entire construction of the coils, this may be conveniently accomplished by means such as is shown in Fig. 25, wherein a bell-crank lever 435 is pivotally mounted on the vertical side plate 198, so that an arm 436 may be actuated into engage-

ment with one of the levers 391 and thereby cause the movement of said levers into the lower position normally occupied upon the energization of the electro-magnet 395. In this position, the 5 levers 391 cannot support the crank arms 383 and 384 when they are raised into their elevated positions by the cam 389 and connected arms 387 and 388.

The operation of the machine as a whole may 10 be summarized as follows. Assuming the apparatus in the starting position shown in the drawings, the actuation of the foot pedal 15 causes the movement of the brush mechanism 29 of the motor 1 from the normal running position to the 15 advanced neutral position, wherein the motor remains at rest even though energized. Upon the movement of the brush mechanism 29 to the neutral position, the crank arm 24 engages the shoulder 27 of the vertical rod 25 shown in Fig. 2 to 20 cause the rocking of the bell-crank lever 28 into the dotted-line position shown in Fig. 4. Such movement permits the spring-pressed switch member 14 to move into the outer circuit-closing position, causing the energization of the driving 25 motor 1, but since the brush mechanism 29 has been advanced previously to the neutral position, the motor 1 does not start. When the foot pedal 15 is released, the brush mechanism 29 under the force of the spring 30 tends to return to the normal running position, but such movement is 30 retarded by the door check 19, with the result that the motor 1 starts slowly from rest and accelerates uniformly to maximum driving speed.

As the speed of the motor 1 is increasing, 35 the traverse cam 73 causes the actuation of the traverse bar 55 to the left, as viewed in Fig. 1, so that single-layers of wire are simultaneously wound in separated zones on a core 436 of the spindle 34. In the particular machine illustrated, eight such separate layers are wound, of 40 which four are in alignment with the sheet-supporting plate 285 and four are in alignment with the sheet-supporting plate 286. Thus, the initial load on the wires due to the starting operation is materially decreased not only by reason 45 of the uniform acceleration in the speed of the winding spindle 34 but also by reason of the wire-tensioning means which moves as shown in Fig. 16 from the solid-line position to, say, the dotted-line position during the starting operation. During such movement, the brake for the spools 111 is disengaged therefrom, so that the 50 spools 111 may rotate freely.

While the traverse bar 55 has been completing 55 the working stroke just-described, superposed sheets of windable material of sufficient length to extend once around the first layer of wire have been positioned on the sheet-supporting plates 285 and 286 ready for delivery to the winding 60 spindle 34 at about the end of the stroke of the traverse bar 55.

The several steps in the formation of these 65 sheets are as follows. The draw bars associated with the pairs of rolls 145, 146 and 147, 148 are actuated downwardly by the vertical rod 179 into the dotted-line position shown in Fig. 33 to draw supplies of paper therefrom. In the meantime, the cam 221 has caused the actuation of the arm 228 and the spring-pressed pawl 229 from the solid-line position shown in Figs. 29 70 and 30 to a position wherein the pawl 229 is at the front edge of the cam 248 carried by the ratchet-wheel 243. The further movement of the cam 221 causes the continued movement of the pawl 229 until it engages the adjustable abutment 251.

This movement of the pawl 229 causes the turning of the ratchet-wheel 231, and, hence, the rotation of the pairs of feed rolls associated with the right and left hand paper-feeding means. As a result, the webs of paper, which have been 80 previously withdrawn from the supply rolls, are now moved through the supply passages, passing therefrom in superposed relation through the knife frames 266 and 282 to the sheet-supporting plates 285 and 286, respectively.

The continued turning of the main cam shaft 184 now causes the reciprocation of the knife frames 266 and 282 through the mechanism shown in Figs. 27 and 28, thereby severing the superposed webs of paper to form superposed sheets of predetermined length. Next, the cam 306 shown in Fig. 25 causes the forward movement of the carriage 283 and, inasmuch as the sheets to be fed to the winding spindle 34 are 90 relatively short, the cam bar 331 is so positioned that the fingers 284 and the roll 325 drop at once into engagement with the paper, and thereby start immediately the forward feeding of the severed sheets in the direction of the winding spindle 34. The operation of the carriage 283 is 95 so timed that the sheets are injected into the coils on the spindle 34 at about the end of the stroke of the traverse bar 55. The traverse cam 73 now causes the movement of the traverse bar 55 with its pairs of guide rollers 105 and 106 100 in the opposite direction to wind a layer of wire on each of the layers of paper just injected into the coils.

Assuming for purposes of illustration that the control mechanism shown in Figs. 35 to 38 is 110 used, the turning of the cross shaft 81 through the pawl-and-ratchet mechanism 409 and 411 causes the movement of the shoulder 417 from the adjustable abutment 418 shown in Fig. 35 to the lever 419, with the result that the switch element 397 is actuated into its circuit-opening position. At this time, the trip lever 403 under the force of the spring 404 moves into the effective position shown in Fig. 38, wherein the movable switch element 397 is held in the open 115 position. The opening of the energizing circuit for the electro-magnet 395 results in an upward movement of the levers 391 under the action of their spring so that when the crank arms 383 and 384 are raised by the cam 389 and connected vertical arms 387 and 388, the shoulders 393 seat in the recesses 392, thereby supporting the arms 383 and 384 in their elevated position. In such position, the right and left hand pairs 120 of upper feed rolls are ineffective, so that sheets 125 of one layer only are formed for delivery to the separate coils under construction on the spindle 34.

In the course of operation of the machine, the 130 sheets of paper delivered to the winding spindle 135 34 are gradually increased in length by the mechanism shown in Figs. 29 and 30. As therein shown, the cam abutment 255 on the main cam shaft 184 causes the intermittent actuation of the pawl 256, and, hence, the movement of the 140 cam 248 so as to increase the effective period of the pawl 229, that is, the period during which the pawl 229 is in engagement with the ratchet-wheel 231. Such increase causes a corresponding increase in the period of operation of the 145 feed rolls and, therefore, the feeding of a greater amount of paper through the knife frames 266 and 282 to form longer sheets.

Simultaneously with the increase in the length 150 of the sheets, the effective stroke of the carriage

283 is decreased due to the gradual forward movement of the cam bar 331. Such movement is caused by the intermittent actuation of the pawl 339 into engagement with the rack 341 formed on the under surface of the cam bar 331, said intermittent actuation being due to the engagement of the cam shoulder 338 with the supporting lever 335 for the pawl 339. As the diameter of the coils on the winding spindle 34 is gradually increased, the front edge of the angularly-adjustable frame 57 is progressively raised by the pawl-and-ratchet mechanism shown in Figs. 7 and 8, which operates through the crank arm 368 to raise vertically the rod 375.

15 When the coils on the winding spindle 34 have been built up to the desired extent, and multiple-layer sheets are again to be supplied thereto, the arm 423 engages an arm 425 of the trip lever 403, as shown in Fig. 38, to cause the disengagement 20 of the other arm 405 of the trip lever from the shoulder 406. The movable switch element 397 is now actuated under the force of the spring 401 into engagement with the stationary switch element 402 to cause the closing of the energizing 25 circuit for the electromagnet 395. Multiple-layer sheets of paper are now supplied in the manner previously described. When the coils have been built up to the desired diameter, the cam shoulder 12 on the counter is actuated into 30 engagement with the pivoted lever 13, causing the movement of the switch member 14 into its circuit-opening position, whereupon the motor 1 is de-energized and the machine comes to rest.

The resetting of the control mechanism shown 35 in Figs. 35 to 38 for the electro-magnet 395, the return of the angularly-adjustable frame 57 and the cam bar 331 to their starting positions shown in Fig. 25, as well as the return of the cam 248 to the starting position shown in Fig. 30 are 40 assured simultaneously, prior to the removal of the spindle 34 from the machine, by the means shown in Fig. 12. When the arm 47 of the bell-crank lever 48 is lowered, the pin 44 carried by the lever 43 is actuated out of engagement with 45 the recess 45 in the crank arm 46, permitting the locking lever 42 to be moved to the right by the center 35 upon the turning of the arm 41. The spindle 34 with the finished coils thereon may 50 now be removed from the machine. It is noted, however, that the movement of the bell-crank lever 48 just mentioned causes the turning of the rock shaft 52, with the result that the pawl 257 is actuated out of engagement with the ratchet-wheel 243 and with it the pawl 256, permitting 55 the ratchet-wheel 243 to return to its original starting position under the force of the spring 244.

At the same time, the holding pawl 348 is actuated out of engagement with the rack 341, so that the weight 332 returns the cam bar 331 to the 60 starting position shown in Fig. 25. Simultaneously, the holding pawl 357, shown in Fig. 8, is actuated out of engagement with the ratchet-wheel 355, the tail portion 358 thereof co-acting with the tail portion 359 of the pawl 354 to render the 65 same also ineffective. The angularly-adjustable frame 57 now returns to the starting position shown in Fig. 25 under its own weight. The rocking of the shaft 52 further causes the pawls 413 and 409 shown in Fig. 35 to be rendered ineffective, whereupon the ratchet-wheel 411 is 70 returned under the force of the tensioned spring 412 to the original starting position shown in this figure. Thus, the depressing of the arm 47 of the bell-crank lever 48 causes the various parts 75 of the machine to return automatically to their

original starting position prior to the removal of the winding spindle 34 from the machine.

If desirable, the spiralling of the last few turns of wire may be increased as shown in Fig. 41, while the machine is in operation, merely by 80 closing the clutch 92, 93. The cross shaft 81, which carries the traverse cam 73, is now actuated through the gear train 87 at an increased speed over that caused normally by the gear train 82.

It will be noted that the invention may be variously modified and embodied within the scope of the subjoined claims.

I claim:

1. A winding machine comprising a winding spindle, means for delivering to said spindle a single sheet, and automatically operative means, whereby a plurality of sheets may be delivered to said spindle. 90

2. In a winding machine, the combination with 95 a winding spindle, of means for simultaneously delivering a plurality of sheets to said spindle, and means automatically operative on said first-mentioned means, whereby a single sheet only may be delivered to said machine.

3. In a winding machine having a winding spindle, the combination with means for delivering to said spindle successive sheets of different length for winding thereon, and means whereby at least one additional sheet may be supplied at 105 a desired point in the operation of the winding machine to form a multiple-layer winding material.

4. In a winding machine having a winding spindle, the combination with means for delivering 110 single sheets of material to said spindle, means for delivering separate superposed sheets to said spindle, control means for said last-mentioned means, whereby single or separate superposed sheets may be simultaneously delivered, and 115 means for progressively changing the length of the sheets during the operation of the machine.

5. In a winding machine having a winding spindle, the combination with automatic means for selectively winding separate superposed sheets 120 or single sheets on said spindle in accordance with a predetermined cycle, and automatic means operative to vary the length of the sheets.

6. In a winding machine having a spindle, the combination with means for winding successive superposed layers of wire thereon, automatic means for winding in predetermined relation to 125 said layers of wire single sheets or separate superposed sheets of insulating material, automatic means for varying the length of the sheets delivered, and means for interrupting the operation of the machine.

7. In a winding machine having a spindle, separate means for feeding separate webs of insulating material to a position wherein portions 130 thereof are in superposed relation, means for severing sheets from said superposed portions, and means for simultaneously feeding said separate superposed sheets to said spindle.

8. In a winding machine having a spindle, 140 means whereby a plurality of superposed layers of wire may be wound on said spindle, a plurality of means for feeding a plurality of webs into superposed relation, common means for severing superposed sheets therefrom, means whereby said 145 superposed sheets may be wound on said spindle at a predetermined point in the formation of the coil, and means for independently controlling the operation of one of said plurality of means.

9. In a coil-winding machine having a spindle, 150

- a plurality of pairs of separable feeding rolls for feeding separate continuous webs, means for severing sheets from said webs adapted for injection into a coil being wound on the machine, and means for varying the spacing between the feeding rolls of one pair to discontinue the feeding of one of said webs. 50
10. In a coil winding machine, having a winding spindle, a wire traverse mechanism, a paper feeding mechanism having a plurality of passages provided with adjacent outlet openings disposed one above the other, means for feeding continuous webs of paper through said passages, and means adjacent to said outlet openings for severing said webs to form superposed sheets, and means for delivering said superimposed sheets to said mandrel. 80
11. In a coil winding machine, having a winding spindle, a wire traverse mechanism, a paper feeding mechanism having a plurality of passages for separate webs of insulating material, a plurality of feeding means for moving the webs through said passages to superposed position, common means for severing sheets from said superposed webs adapted for winding on a spindle, means for rendering one of said feeding means ineffective, and means for delivering said superimposed sheets to said mandrel. 85
12. In a coil-winding machine, a winding spindle, a wire traverse mechanism delivering wire to said spindle so as to form layers of wire thereon, means for feeding insulating material to the spindle between said layers of wire including a pair of feeding and measuring rolls for a web of insulating material, and means for bodily moving one of said rolls to interrupt the feeding of said web comprising a movable member, means for intermittently actuating said movable member, and a magnet having an armature movable into holding engagement with said movable member upon a predetermined actuation thereof. 90
13. In a winding machine, a winding mandrel, means adapted to draw intermittently a supply of paper from a roll, and means for intermittently feeding the paper drawn from said roll to said mandrel, said first-mentioned means comprising an actuating member and loop-forming means, and a lost-motion connection between said actuating member and said loop forming means whereby the loop forming means lies in the loop after actuation to tension the material. 95
14. In a winding machine having a spindle, means adapted to draw intermittently a supply of paper from a roll, severing means, means for intermittently feeding the paper drawn from said roll to said severing means, and means for transferring the severed sheets to said spindle, said first-mentioned means comprising loop forming means and linkage having a lost motion connection with said loop forming means whereby the loop forming means lies in the loop after actuation to tension the material. 105
15. In a coil-winding machine, a winding mandrel, means adapted to draw intermittently a supply of paper from a source to said mandrel, and means for feeding the paper drawn from said source, said first-mentioned means comprising a movable draw bar adapted to form a paper loop and linkage having a lost-motion connection with said draw bar whereby the draw bar lies in the loop after actuation to tension the material. 110
16. In a coil-winding machine, a winding mandrel, a pair of draw bars respectively associated with a pair of paper supply rolls, and means for actuating said draw bars to draw separate loops 115
- of paper from said rolls, comprising actuating means having lost-motion connections with said draw bars whereby said draw bars lie in said loops after actuation to tension the material and means for feeding said supplies of paper to said mandrel. 120
17. In a winding machine, a winding spindle for winding material thereon, sheet-transferring means comprising a movable carriage and a plurality of fingers for said carriage adapted to engage a sheet, each of said fingers being movable about more than one axis during operation. 125
18. In a coil-winding machine having a spindle, means for actuating said spindle, control means for said actuating means, a tail stock having a center movable from a spindle-supporting position to a non-supporting position, and means operatively associated with said center and said control means for preventing the movement of said center between said positions when said control means is in a predetermined position. 130
19. In a coil-winding machine having a removable spindle, means for feeding measured sheets in the direction of said spindle, means for changing the length of said sheets including a movable cam tending to return to its starting position, transfer means for said sheets having a movable control cam tending to return to its starting position, and common means for controlling the return of said cams to their starting positions. 135
20. In a coil-winding machine having a removable spindle, means for feeding measured sheets in the direction of said spindle, means changing the length of said sheets including a movable cam tending to return to its starting position, transfer means for said sheets having a movable control cam tending to return to its starting position, common means for controlling the return of said cams to their starting positions, and means whereby said spindle may be removed from said machine only when said cams are in their starting positions. 140
21. In a coil-winding machine having a removable spindle, means for feeding measured sheets in the direction of said spindle, means for changing the length of said sheets including a movable cam tending to return to its starting position, transfer means for said sheets having a movable control cam tending to return to its starting position, common means for controlling the return of said cams to their starting positions and means whereby additional measured sheets may be supplied to said spindle to provide a multiple-layer winding material, said last-mentioned means having control means interlocked with said common means. 145
22. In a winding machine, a spindle, means for feeding sheets, means for changing the length of said sheets including a movable cam tending to return to its starting position, means for transferring said sheets to said spindle comprising an angularly adjustable sheet-supporting member, automatic means for varying the angular relation of said member with respect to said spindle, said automatic means including trip means permitting the return of said sheet-supporting member to its starting position, and common means for controlling the return of said cam to its starting position and for controlling the operation of said trip means. 150
23. In a winding machine, a removable spindle, means for feeding measured sheets of different length, said means having control elements tending to return to their starting positions, and 155

- means for ensuring the return of said elements to their starting position prior to the removal of said spindle.
24. In a winding machine, a removable spindle, means for feeding single and multiple sheets of different length, said means having control elements, and means whereby said elements may be caused to return to their initial starting positions prior to the removal of said spindle.
- 10 25. A winding machine comprising a winding spindle, means for delivering to said spindle a single sheet, and automatically operable means whereby a plurality of superposed sheets may be simultaneously delivered to said spindle.
- 15 26. A winding machine comprising in combination a winding spindle, mechanism for feeding sheet material to said spindle in single layers, mechanism co-operating with said first named mechanism for feeding separate superposed layers simultaneously to said spindle and means for selectively operating said feeding mechanisms.
- 20 27. In a winding machine, a winding spindle, means for forming successive layers of wire thereon including a wire guiding traverse mechanism, and separate feeding mechanisms for feeding separate layers of paper into superposed position adjacent said spindle, and means for simultaneously delivering said superposed layers in timed relation with the operation of said traverse mechanism.
- 25 28. The combination in a coil winding machine of a winding spindle, means for feeding wire to said spindle including a wire guiding traverse mechanism, means for feeding insulating material to said spindle in timed relation to the operation of said traverse mechanism including separate feeding mechanisms for feeding separate webs of insulating material, means for guiding said webs to position them in superposed relation, means for severing sheets from said superposed webs and means for feeding said superposed sheets simultaneously to said spindle.
- 30 29. The combination in a coil winding machine of a winding spindle, a wire guiding traverse mechanism for delivering wire to said spindle so as to form layers of wire thereon, means for feeding sheets of insulating material to said spindle between said layers of wire including a sheet supporting member, a reciprocating sheet feeding member, and means for moving said sheet feeding member into engagement with a sheet on said supporting member and means for varying the effective stroke of said feeding member with variations in the length of the sheet being fed.
- 35 30. The combination in a coil winding machine of a winding spindle, traverse mechanism for feeding wire to said spindle so as to form layers of wire thereon, means for feeding sheets of insulating material to said spindle between said layers of wire including a sheet transfer means operatively associated with said spindle and having a movable sheet engaging member for feeding a sheet to said spindle, means for supplying sheets of varying length to said transfer means, and means for decreasing the effective stroke of said transfer means in accordance with the increase in the length of said sheets.
- 40 31. The combination in a coil winding machine of a winding spindle, a wire guiding traverse mechanism for feeding wire to said spindle, means for delivering sheet material to said spindle in timed relation to the operation of said traverse mechanism including a sheet supporting member, a reciprocating carriage provided with an actuating member movable into and out of engagement with a sheet on said member, cam means for controlling said actuating member, and means for bodily shifting said cam to vary the feeding stroke of said actuating member.
- 45 32. In a winding machine, a winding spindle, wire traverse mechanism for directing wire to said spindle so as to form layers of wire thereon, means for feeding paper thereto including a pair of separable feeding rolls adapted to receive therebetween a web of paper, means for holding said rolls out of feeding engagement with said paper, means for rendering said holding means ineffective comprising electromagnetic means having a control circuit and means for controlling said circuit in timed relation to the operation of said traverse mechanism.
- 50 33. In a winding machine, a winding spindle, a wire traverse mechanism delivering wire to said spindle so as to form layers of wire thereon, means for feeding sheets of insulating material to said spindle between said layers of wire including a pair of geared feed rolls adapted to receive a web of insulating material therebetween, said rolls being separable to interrupt the feeding operation while maintaining their geared connection, and automatic means for increasing the separation of said rolls and for maintaining said increased separation for a predetermined time interval to interrupt the feeding of said web.
- 55 34. The combination in a coil winding machine of a winding spindle, a wire guiding traverse mechanism for delivering wire to said spindle so as to form layers of wire thereon, means for feeding sheets of insulating material to said spindle between said layers of wire including a sheet transfer means operatively associated with said spindle and having a movable sheet engaging member for feeding a sheet to said spindle, means for supplying sheets of varying length to said transfer means, and means for decreasing the effective stroke of said transfer means in accordance with the increase in the length of said sheets.
- 60 35. The combination in a coil winding machine of a winding spindle, a wire guiding traverse mechanism for delivering wire to said spindle so as to form layers of wire thereon, means for feeding sheets of insulating material to said spindle between said layers of wire including a sheet transfer means operatively associated with said spindle and having a movable sheet engaging member for feeding a sheet to said spindle, means for supplying sheets of varying length to said transfer means, and means for decreasing the effective stroke of said transfer means in accordance with the increase in the length of said sheets.
- 65 36. The combination in a coil winding machine of a winding spindle, a wire guiding traverse mechanism for delivering wire to said spindle so as to form layers of wire thereon, means for feeding sheets of insulating material to said spindle between said layers of wire including a sheet transfer means operatively associated with said spindle and having a movable sheet engaging member for feeding a sheet to said spindle, means for supplying sheets of varying length to said transfer means, and means for decreasing the effective stroke of said transfer means in accordance with the increase in the length of said sheets.
- 70 37. The combination in a coil winding machine of a winding spindle, a wire guiding traverse mechanism for delivering wire to said spindle so as to form layers of wire thereon, means for feeding sheets of insulating material to said spindle between said layers of wire including a sheet transfer means operatively associated with said spindle and having a movable sheet engaging member for feeding a sheet to said spindle, means for supplying sheets of varying length to said transfer means, and means for decreasing the effective stroke of said transfer means in accordance with the increase in the length of said sheets.
- 75 38. The combination in a coil winding machine of a winding spindle, a wire guiding traverse mechanism for delivering wire to said spindle so as to form layers of wire thereon, means for feeding sheets of insulating material to said spindle between said layers of wire including a sheet transfer means operatively associated with said spindle and having a movable sheet engaging member for feeding a sheet to said spindle, means for supplying sheets of varying length to said transfer means, and means for decreasing the effective stroke of said transfer means in accordance with the increase in the length of said sheets.
